UNITED STATES PATENT OFFICE.

PRIMUS W. SMITH, OF JUNCTION CITY, KANSAS, AND JOHN J. BOOKHOUT AND
EDWIN W. MONCE, OF DALLAS, TEXAS.

DRILL-BIT.

1,364,956.

Specification of Letters Patent. Patented Jan. 11, 1921.

Application filed May 10, 1920. Serial No. 380,386.

To all whom it may concern:

Be it known that we, PRIMUS W. SMITH, residing at Junction City, in the county of Geary and State of Kansas, and JOHN J. BOOKHOUT and EDWIN W. MONCE, residing at Dallas, in the county of Dallas and State of Texas, citizens of the United States, have invented certain new and useful Improvements in Drill-Bits, of which the following is a specification.

Our invention has relation to an improvement in drilling bits and in such connection it relates more particularly to the arrangement and construction of such a drilling bit.

The principal object of the invention is to provide a means whereby the driller may at all times have advance knowledge of the formation into which he is about to extend his main hole; it being our purpose, by the use of a smaller device extended below the main drilling blades at any depth desired to find the desired formation with smaller diameter hole and being able to stop at any time with desirable ledge or footing below the drill blades on which casing may rest, thereby avoiding the usual trouble experienced of drilling into oil sand with main bit with no provision for casing seat.

Our invention will be more fully understood by reference to the accompanying drawings forming part hereof, in which—

Figure 1 illustrates a type of assembly of any standard drilling tool equipment, embodying our invention, and showing the manner of attaching by means of threaded connection which may be either tapered or straight.

Fig. 2 is a cross sectional view taken on line 2—2 of Fig. 1.

Fig. 3 is a cross sectional view of Fig. 1 taken on line 3—3 thereof.

Figs. 4, 5, 6 and 7 are detail perspective views respectively of the drilling blades, showing the cutting edges.

Referring more particularly to the drawings, 7 denotes the head of the device into the center of which is projected a threaded connection to receive extension of any standard drilling tool of lesser dimensions than this device and from which extends one or

more drilling points or blades 5, so spaced and dimensioned as to permit the connection of any standard drilling device. Extending above the head 7 is a suitable connection 8 which may be either tapered or straight, 56 internal or external for connecting to main drill stem, and may be of any size required to meet resistance. 10 indicates opening and channels through which water is forced to exhaust through opening 6 which is designed to flush the front or cutting edge of bit thereby keeping a clean surface in front of bit when used on rotary machines. 9 indicates a channel and openings through which water is forced to lower drilling bit 60 to exhaust at 2, when using rotary machine. 12, 14 and 15 are some types of blades which may be used with this class of drilling bit, it being our purpose to use any angle or shape in cutting best designed to 65 successfully negotiate any formation in which we may be working. 7^a is a type of detachable drill bit which is secured to the sides of the drill head and held in position by means of stud screws and keys. 75

Having thus described the nature and objects of our invention, what we claim as new and desire to secure by Letters Patent, is:—

A rotary drilling tool of the character described, comprising a head with drilling blades detachably secured to the head, channels through said head for circulation of water for cleaning the cutting edges of the blades, and a drill stem adapted to be carried below said head and carrying a bit of 80 smaller dimensions and diameter than the main drill bit, the cutting edges of the upper drilling blades arranged equally distant from the center or axis of rotation of the drill stem, the drill stem bit being of such 85 length so as to afford a means of indicating the nature of the formations through which the bit is working and the head being formed to allow the water to carry the cuttings therewith. 90

In testimony whereof we have signed our names to this specification.

PRIMUS W. SMITH.
JOHN J. BOOKHOUT.
EDWIN W. MONCE.
